LOCOMOTIVE STOKER

Andrew M. Hunt, New York, N. Y., assignor to
The Standard Stoker Company, Incorporated,
a corporation of Delaware

Application October 10, 1930. Serial No. 487,651

15 Claims. (Cl. 198—15)

This invention relates to stokers, and particularly to locomotive stokers of the scatter feed type.

It has been customary in those types of stokers 5 in which the riser conduit is offset from the transfer conduit particularly where the screw conveyors in the riser and transfer conduits are independently operated, to have the riser conduit terminate below the transfer conduit, but 10 such a construction is not capable of installation on locomotives in which the height between the frame and cab deck is limited and it is an object of this invention to provide in locomotives, particularly of this latter type a stoker 15 of the offset type which is compact, flexible in operation and capable of practical installation.

It is another object of the invention to provide 20 a stoker of the offset type which will convey fuel from the tender to the locomotive in the most direct course consistent with available space beneath the cab deck of the locomotive.

It is another object of the invention to provide 25 a fuel conveying system in a stoker that is free from obstructions and conveys fuel with a minimum of packing and breaking down.

It is another object of the invention in a stoker of the type described, to provide a riser screw having a multiple threaded lower portion.

It is another object of the invention, in a 30 stoker of the type in which a riser screw delivers fuel to a firebox, to so construct and design the riser casing that fuel is delivered uniformly and evenly therefrom.

To the above and other ends the invention 35 consists in the arrangement of parts and in their relation and association one with the other or in combination as hereinafter described and as illustrated in the accompanying drawings, in which

40 Fig. 1 is a longitudinal, vertical, central section of a locomotive and tender showing the stoker in place in elevation;

Fig. 2 is a plan view of the stoker structure shown in Fig. 1; and

45 Fig. 3 is a plan section on the broken line 3—3 of Fig. 1.

On the drawings the locomotive is generally 50 designated by the numeral 10, and includes the frame 11, the firebox 12, grates 13, the upstanding rear wall or boiler backhead 14 having a firing opening 15 therein at a suitable height above the grates, a boiler mud ring 16 and the cab deck 17 extending rearwardly from the backhead 14.

55 The tender 18 includes a bin 19 having a floor

20 provided with a fuel opening 21 and the usual slide plates 22 mounted in the opening 21, by shifting which fuel may be fed by gravity to the stoker mechanism.

The stoker mechanism includes a rear or 60 transfer section A and a forward or elevator section B. The transfer section A comprises a movable trough 23, supported beneath the opening 21 by rollers 24 on the rails 25 whereby the trough may move longitudinally of the rails 65 and may have a slight angular movement to provide for articulation between the locomotive and tender, and a tubular extension 26 leading forwardly from the trough 23.

The elevator section B comprises a riser conduit 27 opening at its upper end directly to the 70 firing opening 15 and rigidly secured to the backhead 14 by any suitable fastening means through the laterally extending flanges 28, 28a, and the chamber 31 of the casting 29 which 75 forms the base of the elevator and communicates with the forward end of the transfer section A through the elbow 30 of the casting 29. The riser conduit 27 extends rearwardly and downwardly from the firing opening for a short distance 80 along the vertical plane passed through the center line of the locomotive forming a mouth portion or delivery portion 32 and then curves gently to one side of the vertical plane terminating below the cab deck 17 and being 85 received in the seat 33 formed in the wall of the chamber 31 of the casting 29. The elbow 30 of the casting 29 terminates at its rearward end in a spherical flanged seat 34 adapted to receive the ball member 35 carried by the tubular extension 26, whereby a flexible connection between the elbow and tubular extension is formed.

The elevator section B is supported at its lower end in a suitable manner as by the rod 36 95 bolted at one end to the mud ring 16 and at the other end to the flange 37 depending from the casting 29, and further supported from the frame 11 by the expansion plate 38. Preferably, the elevator section B is inclined at an angle 100 with the horizontal of less than 45° to permit the endwise delivery of fuel into the firing opening and the use of a universal joint driving connection at its base as will presently appear.

The sidewalls of that part of the riser conduit 105 27 which extends along the center line of the locomotive flare laterally forward to permit sidewise spreading of the fuel as it is delivered to the firing opening. The upper portion of the riser conduit is provided with the hinged cover 110

39 whereby access may be had to the interior of the riser.

5 Suitable means is provided for advancing the fuel through the conduit system from the bin 19 to the firebox 12. The conveying means comprises separated screw conveyors, the screw 40 being rotatably mounted in the transfer section A and terminating at its forward end adjacent the ball member 35 of the tubular 10 extension 26, and an elevating screw 41 being rotatably mounted in the elevator section B independent of the screw 40, its lower end terminating in the chamber 31 of the casting 29 and its upper end terminating adjacent the 15 bend in the riser conduit 27.

A crusher 42 for use in cooperation with the screw 40 is provided and disposed in the trough 23 for breaking down those lumps of fuel too large for delivery to the firebox.

20 Motion may be imparted to the screw conveyors by any suitable mechanism, but preferably, from a motor 43 located on the forward left hand corner of the tender. The motor 43 is provided with a crank shaft 44 extending to 25 opposite sides of the motor casing and is flexibly connected at its rearward end by the universal joint 45 with the rearward end of the extensible drive shaft 46. The drive shaft 46 is connected at its rearward end in the known 30 and usual manner with the rearward end of the screw conveyor 40 through gearing, not shown, for transmitting motion thereto. The end of the crank shaft 44 opposite the joint 45 transmits motion to the screw 41 through the 35 gearing 47 in the gear casing 48 which is detachably secured to the driving motor 43, and the extensible drive shaft 49 which is universally connected at its rearward end by the joint 50 to a gear shaft 51 and at its forward end by 40 the joint 52 to the screw shaft 53 mounted in a bearing 54 of the chamber 31.

In the operation of the stoker device of this 45 invention, fuel from the bin 19 drops into the trough portion 23 of the transfer section A and is advanced forwardly by the screw 40 past the crusher 42 into the tubular extension 26, the fuel being urged from the end of the screw 40 through the elbow 30 into the chamber 31 and onto the screw 41 whereby the fuel is then elevated in a substantially straight line to the firing opening 15, there the fuel being scattered over the grates 13 by the distributing means including the pressure fluid jet structure 55 and the distributor plate 56.

55 It is known that a helicoid screw will deliver more fuel to one side than to the other. Thus, a screw that advances fuel forwardly when rotated in a right hand direction has a tendency to deliver most of its charge to the left side of 60 its center line and vice versa. Advantage is taken of this fact in the present construction in delivering fuel from the transfer section A to the elevator section B through the elbow 30. From the figures it will be seen that viewing 65 the stoker forwardly, the lower end of the elevator section is offset to the left of the forward end of the transfer section, thus by revolving the screw 40 in a clockwise or right hand direction and having its flights formed to advance 70 fuel, more fuel is delivered to the left side of the center line of the screw 40 whereby the fuel is directed and urged towards the screw 41 in the elevator section. In the construction shown the uneven delivery of fuel to the distributor plate is prevented and fuel is delivered uniform-

ly and evenly permitting even and uniform distribution of fuel over the grates. As may best be seen from Fig. 3, the screw 41, when rotated in clockwise direction to advance fuel, will tend to deliver a heavier charge of fuel to the left of its center line, and this is compensated for by the angular displacement to the left of the upper portion of the riser conduit 27.

To further prevent the accumulation, packing and breaking down of fuel in the elbow 30, the lower portion or fuel receiving portion of the screw 41 is preferably formed with a plurality of threads, whereby the fuel is carried away as rapidly as it is delivered to the screw.

It will be seen that the stoker of this invention is very compact, extremely flexible in operation and capable of practical installation on locomotives in which the distance between the frame and cab deck is limited. The path of the fuel through the conveying mechanism is free of obstructions and sharp bends or turns resulting in a minimum of packing and crushing, and fuel is delivered uniformly and evenly to the distributor plate from where it may be evenly scattered over the fire.

I claim:

1. A fuel elevator for a stoker adapted to receive fuel at its lower portion comprising a riser casing and a screw conveyor rotatably mounted therein, the fuel receiving portion of said screw conveyor being provided with a plurality of threads.

2. A fuel elevator for a stoker adapted to receive fuel at its lower portion comprising a bent riser casing having its lower portion disposed laterally at an angle with respect to its upper portion, and a helical screw rotatably mounted in the lower portion of said riser casing, the flights and direction of rotation of said screw being arranged to deliver the greater portion of its charge to the side of its center line adjacent the inner side of the bend in said riser, and the fuel receiving portion of said helical screw being provided with a plurality of threads.

3. In a stoker, a conveying system comprising a transfer section and an elevator section, said elevator section communicating at its lower end with said transfer section and offset therefrom, a screw conveyor in said transfer section and a screw conveyor in said elevator section arranged to receive fuel at its lower portion from said transfer conveyor screw, said fuel receiving portion of said elevator screw being provided with a plurality of threads.

4. The combination with a locomotive having a firebox with a firing opening and a tender having a fuel bin, of a stoker conveying system including a transfer section mounted on the tender and arranged to receive fuel from said bin, a riser conduit communicating at its upper end with said firing opening and having its lower end offset in a horizontal plane from the forward end of said transfer section, and arranged to elevate fuel in a straight inclined plane from the point of reception into said firing opening, and an intermediate casing connecting said riser conduit and said transfer section, the forward portion of said intermediate casing forming a base for said riser conduit and the rearward portion a laterally curving elbow flexibly attached to said transfer section.

5. The combination with a locomotive having a firebox with a firing opening and a tender having a fuel bin, of a stoker conveying system including a fuel transfer section mounted on the

- tender and arranged to receive fuel from said bin, a fuel elevator section having its upper end on the longitudinal centerline of the locomotive and in communication with said firing opening and its lower end offset laterally in a horizontal plane from the forward end of said transfer section, the lowermost portion of the rearward end of said elevator section being disposed in a plane above the lowermost portion of the forward end of said transfer section, said elevator section being inclined from said transfer section at an angle less than 45 degrees, a laterally and upwardly curving elbow connecting the offset ends of said elevator and said transfer sections, and separated screw conveyors in said transfer and said elevator sections whereby fuel is urged through said elbow from the forward end of said transfer conveyor directly onto the flights of the lower portion of the elevator screw conveyor, the lower end of the screw in said elevator being disposed slightly above the level of the lower forward end of the screw in the transfer section. 5
6. The combination with a locomotive having a firebox with a firing opening and a tender having a fuel bin, of a stoker conveying system including a fuel transfer section mounted on the tender and arranged to receive fuel from said bin, a fuel elevator section having its upper end in communication with said firing opening and its lower end offset in a horizontal plane from the forward end of said transfer section, a laterally curving elbow connecting said transfer and said elevator sections, a screw conveyor in said transfer section and a screw conveyor in said elevator section having a multiple threaded lower fuel receiving portion whereby fuel is urged through said elbow from the forward end of said transfer conveyor screw directly onto the multiple threaded portion of the elevator screw conveyor. 10
7. In a stoker for a furnace having a firing opening, a fuel conveying system including a horizontal fuel transfer section and an elevator section extending downwardly and rearwardly from said firing opening, the mouth portion thereof lying along the same vertical plane that passes through the longitudinal center line of said transfer section, and the lower portion thereof bent laterally from said mouth portion and extending in the same downward and rearward direction, terminating adjacent and at one side of the forward portion of said transfer section and communicating therewith. 15
8. The combination with a locomotive having a firebox with a firing opening and a tender having a fuel bin, of a stoker conveying system including a fuel transfer section mounted on the tender and arranged to receive fuel from said bin and a fuel elevator section extending downwardly and rearwardly from said firing opening along the vertical plane passed through the center line of the locomotive for a portion of its length, and for the remainder of its length angularly disposed thereto, and having its lower end communicating with and offset in a horizontal plane from the forward end of said transfer section. 20
9. In a stoker for a furnace having a firing opening, a fuel conveying system including a fuel transfer section, an elevator section extending downwardly and rearwardly from said firing opening, the upper portion thereof being in axial alignment with said firing opening and opening endwise into the same and the lower portion
- thereof bent laterally from said upper portion terminating adjacent and at one side of the forward portion of said transfer section and communicating therewith, a screw conveyor in said transfer section, and a screw conveyor in said lower portion only of said elevator section. 25
10. In a stoker for a furnace having a firing opening, a fuel conveying system including a fuel transfer section, an elevator section extending downwardly and rearwardly from said firing opening, the upper portion thereof being in axial alignment with said firing opening and opening endwise into the same and the lower portion thereof bent laterally from said upper portion terminating adjacent and at one side of the forward end of said transfer section and communicating therewith, a screw conveyor in said transfer section, and a screw conveyor in said lower portion only of said elevator section, said last named screw having its lower portion provided with a plurality of threads. 30
11. The combination with a locomotive having a firebox with a firing opening and a tender having a fuel bin, of a stoker conveying system including a fuel transfer section mounted on the tender and lying in the vertical plane passing through the center line of the locomotive and tender, a laterally bent elevator section having its lower end offset in a horizontal plane from the forward end of said transfer section and extending upwardly and forwardly to said vertical plane then substantially along said vertical plane to said firing opening, a helical screw in said transfer section and a helical screw in said elevator section terminating at its upper end adjacent the bend in said elevator section, the flights and direction of rotation of said transfer section screw being arranged to deliver most of its charge to that side of its center line nearest the elevator screw, and the flights and direction of rotation of said elevator screw being arranged to deliver most of its charge to that side of its center line adjacent the inner side of the bend in said elevator section. 35
12. The combination with a locomotive having a firebox with a firing opening and a tender having a fuel bin, of a stoker conveyor system including a fuel transfer section mounted on the tender and arranged to receive fuel from said bin, a riser conduit extending downwardly and rearwardly from said firing opening, the upper portion thereof lying in the vertical plane passed through the center line of the locomotive and the lower portion disposed angularly thereto, and an irregular casing connecting said riser conduit and said transfer section, the forward portion thereof forming a base for said riser conduit and the rearward portion thereof forming a laterally curving elbow flexibly connected to said transfer section. 40
13. The combination with a locomotive having a firebox with a firing opening and a tender having a fuel bin, of a stoker conveying system including a fuel transfer section mounted on the tender and extending longitudinally forward, a fuel elevator section having its lower end offset in a horizontal plane from the forward end of said transfer section and its upper end in communication with said firing opening, a laterally curving elbow connecting the offset ends of said elevator and said transfer sections, and a helical screw in said transfer section having the direction of its flights and the direction of its rotation arranged to propel most of its charge as it leaves the final turn of the screw flight in the 45
14. The combination with a locomotive having a firebox with a firing opening and a tender having a fuel bin, of a stoker conveying system including a fuel transfer section mounted on the tender and extending longitudinally forward, a fuel elevator section having its lower end offset in a horizontal plane from the forward end of said transfer section and its upper end in communication with said firing opening, a laterally curving elbow connecting the offset ends of said elevator and said transfer sections, and a helical screw in said transfer section having the direction of its flights and the direction of its rotation arranged to propel most of its charge as it leaves the final turn of the screw flight in the 50
15. The combination with a locomotive having a firebox with a firing opening and a tender having a fuel bin, of a stoker conveying system including a fuel transfer section mounted on the tender and extending longitudinally forward, a fuel elevator section having its lower end offset in a horizontal plane from the forward end of said transfer section and its upper end in communication with said firing opening, a laterally curving elbow connecting the offset ends of said elevator and said transfer sections, and a helical screw in said transfer section having the direction of its flights and the direction of its rotation arranged to propel most of its charge as it leaves the final turn of the screw flight in the 55

direction of the offset end of said elevator section.

14. The combination with a locomotive having a firebox with a firing opening and a tender having a fuel bin, of a stoker conveying system including a transfer section mounted on the tender and arranged to receive fuel from said bin, a riser conduit communicating at its upper end with said firing opening and having its lower end offset laterally in a horizontal plane from the forward end of said transfer section, the lowermost portion of the rearward end of said riser conduit being disposed in a plane above the lowermost portion of the forward end of said transfer section, said riser conduit being arranged to elevate the fuel in a straight inclined plane from the point of reception to said firing opening and an intermediate casing connecting said riser conduit and said transfer section, the forward portion of said intermediate casing being formed rigidly with said riser

conduit and the rearward portion being flexibly associated with the forward end of said transfer section.

15. The combination with a locomotive having a firebox with a firing opening and a tender having a fuel bin, of a stoker conveyor system including a fuel transfer section mounted on the tender and arranged to receive fuel from said bin, a riser conduit extending downwardly and rearwardly from said firing opening, the upper portion thereof lying in the vertical plane passed through the center line of the locomotive and the lower portion disposed angularly thereto, and an irregular casing connecting said riser conduit and said transfer section, the forward portion thereof being formed rigidly with said riser conduit and the rearward portion thereof forming a laterally curving elbow flexibly associated with the forward end of said transfer section.
